UNITED STATES PATENT OFFICE.

OSCAR F. BURTON, OF BELLEVILLE, NEW JERSEY.

ELEVATOR-BRAKE.

SPECIFICATION forming part of Letters Patent No. 661,754, dated November 13, 1900.

Application filed July 28, 1899. Serial No. 725,351. (No model.)

To all whom it may concern:

Be it known that I, OSCAR F. BURTON, a citizen of the United States, residing at Belleville, in the county of Essex and State of New Jersey, have invented certain new and useful Improvements in Elevator-Brakes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to accident-brakes for elevators. By this term "accident-brake" as compared with an ordinary brake as used to diminish the speed of any moving body I mean a brake which will stop the moving body—in this instance, an elevator-car—immediately. The principle underlying my improved brake is gravitation—that is, at the moment when the hoisting-cable breaks the car will be in a state of equilibrium caused by a counterbalancing-weight being attached, which forms with the actual and direct means the brake-block and the brake-lever, a part of my improved brake means, as will be more fully understood as the description proceeds.

In describing my improved brake I shall call attention to the accompanying drawings, where like letters of reference indicate corresponding parts in both views.

Figure 1 is a side view of an elevator, the guides being broken partly away, showing the hoisting-cable in operation, my improved brake means attached in the position they will be in ready to stop the car in case the hoisting-cable should snap. Fig. 2 is an elevation from the same point of view as Fig. 1, the hoisting-cable, however, being broken, thus illustrating my improved brake in operation, holding the car suspended immediately after the snapping of the hoisting-cable.

In the drawings, A indicates the elevator-car, and B the hoisting-cable, attached to the car and passing over the sheave C, secured on the top of the framework E, said cable having the usual counterweights attached. (Not shown or described, as they form no part of my invention.)

D is a standing cable secured fittingly at the top of framework E and at the bottom to

the ring F. In order to avoid the sudden sharp strain on the standing cable D attendant upon the action of my improved brake means on said cable, a spring S, of some resilient material, is secured between the framework E and the disk H, forming part of the means of attachment for the standing cable D at the top, and a turnbuckle I is attached at the lower end of the cable to give the said cable the proper tension. Passing over a sheave J, attached on the top of framework E, is a cable K, to one end of which a counterweight L is attached, the other end being secured fittingly to my improved brake-lever M. The brake-lever M is bolted, by means of the bolt M', to one end of the link N, the other end of the brake-lever being bolted to my improved brake-block P by means of a bolt P'. The link N is pivotally attached at its other end to a bearing-block O, said block secured on the top of the elevator-car A.

The brake-lever M is constructed as follows: The arm M² is furnished with a head M⁴, having as swelling, said swelling moving eccentrically with regard to the pivot P' and having its edge when the brake means are called into action pressed against the standing cable D, so as to cause a bend in the said cable, as seen in Fig. 2. The other arm M³ of the brake-lever M is located between two bushes B' and B², firmly secured to the hoisting-cable B, and is to that effect forked, a prong of such fork lying on either side of the cable, the object of said bushes being to keep the lever M in an appropriate horizontal position. The brake-block P is furnished with the sheaves Q' to Q⁶ and is, as before stated, pivotally attached to the brake-lever M by means of the bolt P' in the head M⁴. Of the sheaves Q' to Q⁶ it will be seen that Q⁵ and Q⁶ and Q³ and Q⁴, respectively, lie in pairs on either side of the standing cable D, acting thus in the capacity of guiding-sheaves and, further, preventing any friction on said cable. Sheaves Q' and Q², placed, as they are, adjacent to and with the head M⁴ touching the standing cable opposite to and between them, will, in connection with the said swelling, jam the part R of the standing cable thus lying between them, as will be more fully understood when the operation of my improved brake means are described in coöperative unison.

It can now be understood from the description of the above elements that as long as the hoisting-cable B is in operative order and carries the elevator-car A up and down the counterweight L and the car A simply move correspondingly without the weight of either coming into play, the brake elements then being in rest, as seen in Fig. 1. When observing Fig. 2, the coöperation of the brake elements with each other is as follows: The link N, attached to the car A by means of the bearing-block O, has at its other end the brake-lever M pivotally attached to it, said lever further having the cable K secured to it, which cable K, passing over the sheave J, has at its other end the counterweight L attached. As the brake-block P is pivotally connected to the brake-lever M, it will be readily seen that it moves conjointly with said lever, the sheaves Q' to Q⁶ guiding it up and down the standing cable. Taking now the position illustrated in Fig. 2, showing the hoisting-cable snapped, it will be seen that the weight of the car A will when unsupported by the hoisting-cable B force the arm M³ of the brake-lever downward by reason of the connection existing between the lever M and the car A by means of the metallic link N. This downward movement of the arm M³ results in a turning of the lower curve of the swelling on the head M⁴, so as to force the (standing) part R of the standing cable lying between said swelling and the sheaves Q' and Q² over against such sheaves and jamming it tightly there, the car further being counterbalanced and held in equilibrium by the counterweight L now having come into full

play with the separation from the hoisting-cable. The main features productive of this result will consequently be seen to be a brake-lever furnished with a head having a swelling caused to move eccentrically around a certain pivot when the hoisting-cable breaks and connected with a counterbalancing cable and weight, said brake-lever pivoted to a 45 brake-block guided along the standing cable.

I might state here that the brake-lever, the brake-block, and the link connecting the brake-lever with the elevator-car are made of metal, as constituting the only material durable and strong enough to fulfil the functions demanded of said elements. In these above-mentioned means the main features of my invention are thus embodied, and

What I therefore claim in accordance with 55 such description is—

The combination with an elevator-car, its hoisting and counterbalance cables and a standing cable; of the metallic brake-lever M operated directly by the weight of the car 60 so as to grip the standing cable and having the hoisting-cable connected directly therewith, the metallic brake-block P having the said lever M pivoted thereto and the metallic connecting-link N pivotally connected to the 65 car and the brake-lever M substantially as described.

In testimony that I claim the foregoing I have hereunto set my hand this 27th day of July, A. D. 1899.

OSCAR F. BURTON.
